United States Patent Office

Des. 183,338
Patented Aug. 12, 1958

183,338

SEAT BELT BUCKLE

Lloyd L. Anderson, Grand Rapids, Mich., assignor to
Jervis Corporation, Grandville, Mich., a corporation
of Michigan

Application December 23, 1955, Serial No. 39,463

Term of patent 14 years

(Cl. D17—1)

Fig. 1.

Fig. 2.

Fig. 3.

Fig. 4.

Fig. 5.

Fig. 1 is a top plan view of a seat belt buckle embodying my new design;

Fig. 2 is a front elevational view thereof;

Fig. 3 is a bottom plan view thereof;

Fig. 4 is an enlarged end elevational view taken on the line 4—4 of Fig. 2; and

Fig. 5 is a perspective view of the seat belt buckle.

In all figures, the adjacent belt portions are shown in dotted lines for purposes of illustration.

I claim:

The ornamental design for a seat belt buckle, substantially as shown and described.

UNITED STATES PATENT OFFICE
CERTIFICATE OF CORRECTION

Design No. 183,338

August 12, 1958

Lloyd L. Anderson

It is hereby certified that error appears in the printed specification of the above numbered patent requiring correction and that the said Letters Patent should read as corrected below.

Column 2, lines 2 and 3, for "The ornamental design for a seat belt buckle, substantially as shown and described." read -- The ornamental design for a seat belt buckle or similar article, substantially as shown and described. --.

Signed and sealed this 28th day of October 1958.

(SEAL)
